UNITED STATES PATENT OFFICE.

THOMAS W. HOUCHEIN, OF NEW YORK, N. Y.

FOLDING POCKET COOK-STOVE.

SPECIFICATION forming part of Letters Patent No. 274,380, dated March 20, 1883.

Application filed December 9, 1882. (No model.)

To all whom it may concern:

Be it known that I, THOMAS W. HOUCHEIN, of New York, in the county of New York and State of New York, have invented certain new and useful Improvements in Folding Pocket Cook-Stoves; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 represents an elevation of the device in position for use; Fig. 2, a top view, looking down on the frame, the boiler being removed; Fig. 3, an enlarged view, showing the construction of the frame; Fig. 4, a detail showing the locking-handles of the boiler. Fig. 5 shows the standards folded; Figs. 6 and 7, sections of the lamp. Figs. 8, 9, and 10 show the method of making the handle-sockets.

This invention relates to improvements in folding pocket cook-stoves. Its object is to simplify and cheapen their construction, to render them better for wear, and handier in use.

The invention consists in the peculiarities of construction and arrangement of parts hereinafter set forth.

In the annexed drawings, the letter A represents the lamp support or frame, consisting of two or more standards jointed together. In the present instance three standards, B B' B², are shown, made alike. These standards are constructed usually from sheet metal, and are given the shape indicated. At the middle they are provided with the openings b, having the straight bottom edges, b', and the curved top edges, b², these openings forming the lamp-seats. At their corners a these standards are provided with the holes a', which are made preferably longer vertically than across. In these holes are placed the rings C, which are made cylindrical, as shown, and fit snugly.

These rings form the joints or hinges by which the standards are held together. By means of these rings the edges of the standards B B' and B' B² are held together permanently; but the meeting edges of standards B and B² are not so connected. These edges have the holes a'; but they are connected by the catches D, as shown in Figs. 1 and 2. These catches

have the shape therein shown. They are curved so as to have the bends d and d'.

In using the frame as a support for the lamp E the latter is surrounded by the frame resting in the seats b, the standards readily turning on their hinges and closing around the lamp. In this position the frame is locked by fastening the catches D, as shown in Fig. 2. In case the frame should be turned upon itself in the opposite direction from that shown in Fig. 2, the catches would still operate to hold it, as the curve d' would readily slip into the hole a' adapted for receiving the catches, so that the frame can be locked in whichever direction it may be turned.

There is no danger of putting the lamp in upside down. For if the lamp should be placed in the seats with its bottom to their curved edges it would not fit snugly, and the standards would not come together and fasten.

As shown in Figs. 6 and 7, the lamp E is provided at its top with a wall, e, all around. This is part of the shell of the lamp, and forms a large recess or receptacle at the top, above the gage or center-piece e', so that in pouring in alcohol there is no danger of overflow while it is soaking into the asbestos or other material in the lamp. As shown, this wall may be constructed in several ways: In Fig. 6 the shell is turned down and terminates in a lip, e², all around the center-piece; in Fig. 7 the wall terminates at the top, e⁴, instead of being turned down. Upon the wall e is placed the lamp-cover F.

With this stove a boiler, H, is to be used. This boiler has certain peculiarities of construction which render it cheap and handy. Its handles K slip and pass the other, interlocking and being held firmly, and its body L has one of its ends turned upon itself, forming the sockets for the ends of the handles.

No claim is made in this application for the peculiar construction of the handles and boiler, the right to make any such claim being reserved for another application.

The construction described furnishes a simple and useful stove.

The standards can be folded, as shown in Fig. 5, and snugly packed away, and the handles K folded about the boiler.

The lamp is of a size to fit inside the boiler, and the stove-frame, when folded, has about

the same area as the boiler, so that they all can be conveniently packed in a box small enough to be placed in an ordinary pocket. A gridiron can also be packed therein and used for cooking, when desired.

Having described my invention, what I claim is—

1. In a pocket cook-stove, a folding frame provided with the lamp-seats, as set forth.
- 10 2. The standards B B' B², having the seats b, as set forth.
3. The standard B, having the seat b, pro-

vided with a straight edge, b', and a curved edge, b², as set forth.

4. The standards B B' B², having the hole 15 a', and the rings C, in combination with the catches D, as set forth.

In testimony that I claim the foregoing as my own I affix my signature in presence of two witnesses.

THOMAS W. HOUCHIN.
